DRYING LINE AND SELF-LOCKING REEL
THEREFOR

Anne D. Hanna, Los Angeles, Calif.

Application January 1, 1945, Serial No. 570,967

13 Claims. (Cl. 242—100)

1

This invention relates to supporting devices, and particularly to a supporting device of the clothesline type, which is quickly attachable and detachable to walls, posts, or any reasonably smooth surface.

The use of vacuum cups for attaching clothes hooks or other supporting members to smooth surfaces is well known, as evidenced by U. S. Patents No. 1,714,422 of May 21, 1929, and No. 2,225,681 of December 24, 1940. The present invention is of this general type, but one which carries a portable drying line for wet clothes or other articles to be hung up for temporary periods and which is particularly suitable for traveling.

In addition to the vacuum cup attachment, an important feature of the invention is the method of and means for retaining the cord or line which is suspended between two vacuum cups or between one vacuum cup and another support. The cord or line is wound on a reel or sheave which not only serves as a keeper spool for the line, but also is so constructed as to provide a lock for the reel to fixedly hold any length of line being used. The vacuum cups, reel, and line are so constructed that all elements may be conveniently carried in a traveling bag or ladies' purse and quickly attached and detached to the walls of dressing rooms, sleeping compartments or berths of trains, or to the walls or other smooth surfaces of bathrooms or kitchens in the home. As will be explained in detail hereinafter, the device may be readily put in use and the line quickly wound back on the reel attached to one of the vacuum cups.

The principal object of the invention, therefore, is to provide an improved portable drying line for clothes or similar articles.

Another object of the invention is to provide an improved drying line and supporting reel and lock therefor.

A further object of the invention is to provide an improved drying line support, one which is easily attachable and detachable, with the length of line readily adjustable to various lengths.

A still further object of the invention is to provide an improved reel device which is self-locking.

Although the novel features which are believed to be characteristic of this invention will be pointed out with particularity in the appended claims, the manner of its organization and the mode of its operation will be better understood by referring to the following description read in conjunction with the accompanying drawings forming a part hereof in which:

2

Fig. 1 is a view showing the device set up for use.

Fig. 2 is an end view of one of the embodiments of the reel mechanism of the invention.

Fig. 3 is a cross sectional view of the embodiment shown in Fig. 2.

Fig. 4 is a detail view of the embodiment of Figs. 2 and 3, showing the reel in locked position.

Fig. 5 is a perspective view of a second embodiment of the invention.

Fig. 6 is a cross sectional view of the reel shown in Fig. 5.

Fig. 7 is a detail view of the hub for the reel of Fig. 5.

Fig. 8 is a perspective view of a third embodiment of the invention.

Fig. 9 is a cross sectional view of the reel shown in Fig. 8, and

Fig. 10 is a perspective view of the attachment for the end of the line of any of the above embodiments.

Since the primary purpose of the invention is to provide a quickly attachable and detachable drying line, Fig. 1 shows a reel carrying vacuum cup 5 attached to a wall 6, and a vacuum cup 7 with a hook 28 (see Fig. 10) attached to wall 8 with a line 10 extending between the two cups for the purpose of supporting wet clothes and the like. The reel cup 5 is larger than cup 7, since it carries the reel, but the size of both cups will depend upon the weight of the material to be supported by the line.

Referring now to Figs. 2, 3, and 4 wherein one embodiment of the invention is illustrated, it will be noted that vacuum cup 5 is of the well-known circular type with flexible outer edges, a tip 13 being provided for the purpose of breaking the vacuum when the cup 5 is to be detached. Molded in the hub 15 of the cup 5 are the split and flared ends 18 of a reel hub or axle 17, the outer portion being a serrated disc with inwardly extending locking projections 26.

The line supporting reel is composed of a plurality of radial ribs or spokes 23 with a solid center disc section, as shown by the dotted lines 19 in Fig. 2, the inner edge 12 of the disc being expanded at right angles to form a bearing portion for the reel. The edge of bearing 12 abuts a washer 21 positioned on the hub 17 and against the cup hub 15. The cord or line 10 is wound in the channel formed by bending the radial members 23 downwardly and upwardly with flat portions 25. The ends of the members may be sharply bent to accommodate a disc 27 to stiffen

the reel. The disc 27 may be eliminated if the spokes 23 are of heavy gage material.

To unreel the line 10, the reel is simply rotated when in the position shown in Fig. 3 to allow the line 10 to be unwound, extended, and fastened to the hook 28 of the cup 7. The end of the line 10 may have a ring 30 attached thereto, as shown in Fig. 2, the ring, of course, being attachable to any other supporting means as well as the cup 7. When the line is drawn fairly taut, the tension on the line moves the reel radially along the hub 17 so that the extensions 26 may enter between the spokes 23 of the reel, as shown in Fig. 4. Since the hub 17 is fixedly mounted, the reel will be locked in position, and no further length of line can be unwound. Thus, an automatic lock is provided between the reel supporting hub or axle and the reel itself, which is adjustable within an angle of sixty degrees when six spokes are employed. It will be noted that the ends or edges of the projections 26 are saw-toothed so that a ratchet action is obtained to move the reel to rotating position when it is desired to rewind or tighten the line.

Referring now to Figs. 5, 6, and 7 in which a second reel construction is illustrated, the reel carrying vacuum cup 5 is provided with a hub or axle member 29 which is cylindrical with split and flared ends 31 imbedded in the hub 15 of the cup 5. The hub 29 has its outer end split into four portions 32 which are bent at right angles to the axis of the hub and in which holes 44 are made. The hub 29 is internally threaded to accommodate a stud 40 on which is fixedly mounted a knob 41 having an annular groove 42 around its inner surface and a radial groove 46. All the elements just described are fixed with respect to the cup 5.

Rotationally mounted on the hub 29 is a reel comprising a U-shaped annular element 34 with a back side flange 35 and a front side flange 36, the latter having an annular rim projection 37, which normally occupies only a portion of the groove 42 in the knob 41. On the face of the front side flange 36 are detent projections 45 adapted to enter holes 44 when the reel 34 is moved axially to the right to lock the reel in non-rotational position. The line 10 is adapted to be wound on the flat section of the member 34.

This reel construction operates in a similar manner to that of the embodiment shown in Figs. 2, 3, and 4. It is only necessary, after the required length of line is unwound from the reel, to place the cord 10 in the slot 46, the tension on the cord 10 sliding the reel 34 axially along the hub 29 until the projections 45 of the reel enter the first adjacent holes 44. Since the knob is stationary, the reel will stay in locked position by the tension on the line 10.

Referring now to the third embodiment of the invention shown in Figs. 8 and 9, the vacuum cup 5 has a cylindrical portion 50 imbedded in the hub 15 of the cup 5, the hub 50 being internally threaded to accommodate the axle 51 on which is mounted a rotatable reel 52 composed of an inner side flange 53 with annular openings 54 adjacent its periphery and an outer side flange 55. The imbedded portion 50 has a flat, flexible, radially extending arm 57 which has an embossed projection 58 and a hooked end portion 59. In this embodiment, the cord or line 10 is wound on the reel 52, and when the cord 10 is extended the proper distance, it is looped around the extension 57 as shown in Fig. 8. This extension, being flexible, will bend toward the side flange 53,

permitting the embossed point 58 to enter one of the perforations or holes 54, which, since the extension 57 is stationary, will keep the reel 52 from rotating.

Thus, all the above embodiments function in the same manner, that is, the end of the line may be attached to either a vacuum cup carrying hook or any other point of support, the line being extended from the reel to the desired length with the tension of the line locking the reel from further rotation. In Figs. 8 and 9, the line is looped around locking arm 57; in Figs. 5, 6, and 7, the line is inserted in notch 46; while in Figs. 2, 3, and 4, the tension of the line slides the reel into locking engagement with the hub extensions 26.

When the line has served its purpose, or it is desired to pack it, the end of the line is simply detached and the line wound on the reels, as explained above. The second vacuum cup used for the attachment of the other end of the line may be attached to the inner flat portion of the reel carrying cup 5, as shown in Fig. 3, for carrying purposes. All of the cups may have projections, such as shown at 13 in Fig. 3, for facilitating the releasing thereof from the surfaces to which they are attached. It is also understood that disc 27 of Fig. 3 may have a radial slot therein, as shown in Figs. 5 and 6, to bring the pull of the line closer to the axis of the reel and hub.

I claim as my invention:

1. A line and reel therefor, comprising a vacuum cup, a hub member extending from said cup, a line, a reel member rotatable on said hub member and on which said line is adapted to be wound, and means for interlocking said reel member and said hub member when said line is tensioned and a component of said tension is along the axis of said hub and reel.

2. A line and reel therefor in accordance with claim 1, in which said reel member is formed of a plurality of radial spokes having U-shaped axial extensions for supporting said line, and said hub member has projections extending between said spokes when said hub member and reel are interlocked.

3. A line and reel therefor in accordance with claim 1, in which said reel member is slidable axially along said hub member, said reel member having projections thereon extending into openings in said hub member for interlocking said hub and reel members.

4. A line and reel therefor in accordance with claim 1, in which said hub member has a flexible radial arm extending therefrom, said arm having a projection therefrom extending into an opening in said reel member when said reel member and said hub member are in interlocking position.

5. A quickly attachable and detachable drying line and reel comprising a vacuum cup, a reel member, an axle member for supporting said reel member, a portion of said axle member being imbedded in said vacuum cup, and means on said axle member having a projection thereon for entering a perforation on said reel member for locking said reel member to said axle member.

6. A line and reel combination comprising a hub member, supporting means for said hub member, one end of said hub being imbedded in said supporting means and the other end of said hub having radially extending flanges thereon, said flanges having openings therein, a line reel mounted for rotation on said hub member, and projections extending from one end of said reel and adjacent said radially extending flanges, said reel member being slidable axially on said hub

member so said projections may enter said openings to lock said reel member to said hub member.

7. A line and reel combination in accordance with claim 6 in which said supporting means for said hub member is a vacuum cup.

8. A line and reel combination comprising a vacuum cup, a cylindrical hub member having one end thereof imbedded in said vacuum cup and the other end having radial flanges extending therefrom, a plurality of spokes having an integral center section mounted on said hub member, and U-shaped outer ends adapted to have a line wound thereon, said spokes being movable axially on said hub member, and a plurality of extensions on said hub flanges parallel to the axis of said hub member and adapted to be interposed between said spokes when said spokes are moved toward said flanges.

9. A line and reel combination in accordance with claim 8 in which said extensions have a diagonal edge to permit said reel to be rotated in one direction only when said line is under tension.

10. A line and reel combination comprising a vacuum cup, an axle having one end imbedded

in said cup, a knob on the other end of said axle, said knob having a larger diameter than said axle and a reel rotatably mounted on said axle, said reel having a line wound thereon and slideable axially on said axle, said knob having a substantially radial slot therein for the insertion of said line.

11. A line and reel combination comprising a hub member, supporting means for said hub member, one end of said hub member being attached to said supporting means, a line, a reel member rotatable on said hub member and on which said line is adapted to be wound, and means for interlocking said reel member and said hub member when said line is tensioned and a component of said tension is along the axis of said hub and reel.

12. A line and reel combination in accordance with claim 11, in which said supporting means for said hub member is a vacuum cup.

13. A line and reel combination in accordance with claim 11, in which said reel member is slideable axially on said hub member to interlock said members.

ANNE D. HANNA.
